UNITED STATES PATENT OFFICE.

GEORGE ALBERT LYON, OF PHILADELPHIA, PENNSYLVANIA.

AUTOMOBILE-BUFFER.

1,325,746.

Specification of Letters Patent. Patented Dec. 23, 1919.

Application filed September 18, 1919. Serial No. 324,294.

To all whom it may concern:

Be it known that I, GEORGE ALBERT LYON, a citizen of the United States, and resident of Philadelphia, county of Philadelphia, 5 State of Pennsylvania, have made a certain new and useful Invention Relating to Automobile-Buffers, of which the following is a specification, taken in connection with the accompanying drawings.

10 This invention which is a continuation in part of my co-pending application, Serial No. 310,937, filed July 15, 1919, that is, contains subject-matter taken therefrom, relates especially to automobile buffers formed 15 of resilient strip steel or other metal and in which one of the co-operating connector portions of the buffer members is preferably formed with low or slightly projecting alining flanges preferably projecting not more 20 than about the thickness of the main strip and having inclined or somewhat wedging inner sides so as to engage and grip the co-operating buffer member which may have a substantially flat cross-section with rounded 25 ends, for instance. When such connector members have their flat faces forced or clamped together by any suitable clamping means these gripping alining flanges can thus exert a very desirable alining action 30 and hold the members against vertical movement so that a relatively slight overlap of these buffer members is sufficient to rigidly and reliably clamp them together. The buffer front or impact receiving member is 35 preferably provided with these alining flanges throughout its length and this member may be formed with integral end loops and with inturned connector portions extending toward each other from the end 40 loops so as to constitute substantially straight connector portions to which the resilient or other attaching members may be adjustably clamped as described. Of course 45 by hardening and tempering such a spring channeled buffer front member a high degree of resilient strength is secured and the alining flanges add to its strength and when only projecting to a relatively slight extent from its surface do not greatly interfere 50 with the bending and forming operations to which the member is subjected.

In the accompanying drawing which shows in a somewhat diagrammatic way an illustrative embodiment of this invention, 55 Figure 1 is a plan view of a buffer; and

Fig. 2 is an enlarged transverse sectional view taken substantially along the line 2—2 of Fig. 1.

The resilient buffer front member as shown in Fig. 1 may consist of a single resilient strip of tempered spring steel, for example, and may have the low flanged channel cross-section shown in Fig. 2 which shows an illustrative proportion of this channel section on substantially a full size 60 scale. These flanges 12 may project a quarter of an inch or so from the flat surface of the member and when rolled or formed with rounded edges as indicated they give a pleasing contour to the buffer front which may 65 thus have a substantially flat front surface with rounded edges. The usual hot bending of the spring channel strip may be effected by bending the strip around a form preferably so shaped as to principally or solely 70 engage the flat inner side of the strip so as to give a minimum deformation to the flanges. Integral end loops, such as 2, 3, may be formed at the end of the buffer front member and these looped portions constituting the ends of the buffer are preferably 75 bent backward somewhat throughout the portions which are adapted to extend into protective position in front of the wheels of the automobile or other vehicle. A desirable way of forming this part of the buffer is to have the portions 4 substantially straight while the inturned connector portion 5 on the other side of the end loop is also preferably straight and approximately 80 parallel or preferably at a slight flaring angle with respect to the adjacent front portion of this buffer end. These end portions may of course merge into the central or front portion 1 of the buffer through intermediate curved portions to give a more 85 pleasing outline and this central part of the buffer front member may be either substantially straight as indicated or slightly forwardly bowed as desired.

The co-operating attaching members connecting the buffer front to the automobile frame or other part of the vehicle may advantageously be formed of resilient strip such as tempered spring steel and these attaching members 8, 9 may each comprise a forwardly and outwardly bent portion 10 merging into a substantially straight connector portion 11 of such size and length as to properly coöperate with the inturned 110

connector portion 5 at that end of the buffer front member, the angle of the connector portion 11 being so related to the rearwardly extending portion of the attaching member 5 that these two attaching members may be substantially parallel while their connector portions properly coöperate with the inturned connector portions of the buffer front member. By this arrangement an overlap 10 of three or four inches or more can be secured between the coöperating connector portions which are adjustably clamped or secured together and at the same time ample range of adjustment can be secured between 15 these substantially straight or otherwise similarly shaped connector portions so that as much as four or five inches adjustment may in some cases be secured at each of these points.

20 Fig. 1 illustrates these connector portions in such adjusted positions as brings the attaching members quite close together and under these conditions a three or four inch overlap beyond the ends 6, 7 of the inturned connector portions of the buffer front member is sufficient where such gripping alining action is secured by making one of the connector portions of flanged cross-section as described. By giving the inner faces or 25 sides of these alining flanges 12 a slightly inclined form the edges of the connector portion 11 of the coöperating attaching member may be forced into wedging engagement therewith when the parts are 30 clamped or forced together so that a very efficient vertical alining action is thus secured by forcing the flat faces of the coöperating members together. Any desired form of clamping means may be used for 35 this purpose and Figs. 1 and 2 illustrate a form of clip 14 which is desirable for this purpose, the inner faces or portions of the clip of malleable iron or drop forged steel, for instance, being so shaped as to embrace 40 the intermediate interlocked connector portions over which the clip may be slipped or forced when in its opened or loosened position. Then by tightening up the clamping bolt 13 which may as indicated be provided with lock washers the parts are forcibly brought together in a horizontal direction whereupon the relatively tight fit of the alining flanges prevents any undesirable or substantial vertical movement and if a 45 gripping or wedging contact is secured between these flanges and the coöperating connector portion an extremely tight and reliable joint may thus be conveniently formed which as stated gives ample stiffness and 50 strength when an overlap of four inches or so is employed even under the extremely trying service conditions to which such automobile buffers are exposed. Of course where such tight fitting or wedging flanges 55 are employed care must be taken in bending

or forming the inturned connector portions of such a spring channel strip so as not to deform them and this is facilitated by making the connector portions substantially straight, and in some cases the hot strip may 70 during the bending operation be forced against accurately fitting dies or formers so as to insure the accurate positioning and spacing of these alining flanges or they may be subsequently ground or otherwise finished and sized, if desired.

This buffer may of course be readily taken apart and put together and adjusted on an automobile by the ordinary chauffeur or car owner without special tools or appliances, it being naturally understood that the attaching members are of such form and construction as to be adapted to be clamped or otherwise secured to the automobile frame. When disconnected the parts of this 80 buffer may be readily packed and stored and shipped which is also an important consideration in this connection.

This invention has been described in connection with a number of embodiments, 90 forms, proportions, parts, arrangements, materials, methods of manufacture, connection and use, to the details of which disclosure the invention is not of course to be limited, since what is claimed as new and 95 what is desired to be secured by Letters Patent is set forth in the appended claims.

I claim—

1. The automobile buffer comprising a resilient buffer front member formed of channel sectioned spring steel strip having slightly projecting gripping alining flanges provided with inclined wedging inner sides, said buffer front member having rearwardly bent integral end loop portions adapted to 100 project into protective position in front of the vehicle wheels and having integral in-turned substantially straight rear connector portions extending inward at a slightly diverging angle to the adjacent front portions 105 of said member, spring steel strip attaching members having forwardly and outwardly curved portions and integral substantially straight connector portions adapted to adjustably coöperate with the inturned connector portions of said buffer front member 110 and have substantially tight wedging engagement with the alining flanges thereof and clamping means inclosing the coöperating connector portions adjacent each end of 115 the buffer and forcing the flat substantially vertical faces of the connector portions together and promoting the vertical alinement of said connector portions.

2. The automobile buffer comprising a resilient buffer front member formed of channel sectioned spring steel strip having projecting gripping alining flanges provided with inclined wedging inner sides, said buffer front member having integral end 125 130

loop portions adapted to project into protective position in front of the vehicle wheels and having integral inturned substantially straight rear connector portions, spring steel strip attaching members having forwardly and outwardly curved portions and integral substantially straight connector portions adapted to coöperate with the inturned connector portions of said buffer front member and have substantial wedging engagement with the alining flanges thereof and clamping means inclosing the coöperating connector portions adjacent each end of the buffer and forcing the flat substantially vertical faces of the connector portions together.

3. The automobile buffer comprising a resilient buffer front member formed of channel sectioned strip having projecting gripping alining flanges provided with inclined wedging inner sides, said buffer front member having integral end loop portions adapted to project into protective position in front of the vehicle wheels and having integral inturned substantially straight rear connector portions, attaching members having integral substantially straight connector portions adapted to coöperate with the inturned connector portions of said buffer front member and have substantial wedging engagement with the alining flanges thereof and clamping means forcing the connector portions together.

4. The automobile buffer comprising a resilient buffer front member formed of channel sectioned spring steel strip having gripping alining edge flanges transversely projecting from the strip not more than the thickness of the strip, said buffer front member having integral loop portions adapted to project into protective position in front of the vehicle wheels and having integral substantially straight connector portions, spring steel strip attaching members having forwardly and outwardly curved portions and integral substantially straight connector portions adapted to coöperate with the connector portions of said buffer front member and having alining action in connection with the alining flanges thereof and clamping means inclosing the coöperating connector portions.

5. The automobile buffer comprising a resilient buffer front member formed of channel sectioned spring steel strip having gripping alining flanges transversely projecting from the strip not more than the thickness of the strip, said buffer front member having integral portions and having integral substantially straight connector portions, attaching members having integral substantially straight connector portions adapted to coöperate with the connector portions of said buffer front member and have alining action in connection with the alining flanges thereof

and clamping means inclosing the coöperating connector portions.

6. The automobile buffer comprising a resilient buffer front member formed of channel sectioned strip having alining flanges, said buffer front member having integral portions and having integral connector portions, attaching members having integral connector portions adapted to coöperate with the connector portions of said buffer front member and have alining action in connection with the alining flanges thereof and clamping means engaging the coöperating connector portions.

7. The automobile buffer comprising a resilient strip buffer front member having end loop portions adapted to project into protective position in front of the vehicle wheels and having integral inturned substantially straight connector portions formed with slightly projecting gripping alining edge flanges provided with inclined wedging inner sides, spring steel strip attaching members having outwardly curved portions and integral substantially straight connector portions adapted to adjustably coöperate with the inturned connector portions of said buffer front member and have substantially tight wedging engagement with the alining flanges thereof and frictional clip clamping means adapted to inclose the coöperating connector portions adjacent each end of the buffer and force the same together.

8. The automobile buffer comprising a resilient strip buffer front member having end loop portions adapted to project into protective position in front of the vehicle wheels and having inturned substantially straight connector portions formed with gripping alining edge flanges provided with wedging inner sides, attaching members having outwardly curved portions and integral substantially straight connector portions adapted to adjustably coöperate with the inturned connector portions of said buffer front member and have substantially tight wedging engagement with the alining flanges thereof and frictional clip clamping means adapted to inclose the coöperating connector portions adjacent each end of the buffer and force the same together.

9. The automobile buffer comprising a resilient strip buffer front member having end loop portions adapted to project into protective position in front of the vehicle wheels and having integral inturned connector portions formed with alining flanges, attaching members having outwardly curved portions and connector portions adapted to adjustably coöperate with the inturned connector portions said buffer front member and the alining flanges thereof and clamping means adapted to engage the coöperating connector portions adjacent each end of the buffer and force the same together.

10. The automobile buffer comprising a buffer front member formed of channel sectioned strip having alining edge flanges, said buffer front member having integral 5 loop portions adapted to project into protective position in front of the vehicle wheels and having inturned integral substantially straight connector portions, spring steel strip attaching members having forwardly and outwardly curved portions and integral substantially straight connector portions adapted to adjustably coöperate with the connector portions of said buffer front member and having alining action in 15 connection with the alining flanges thereof and clamping means securing together the coöperating connector portions.
11. The automobile buffer comprising a buffer front member formed of channel sectioned strip having alining flanges, said buffer front member having integral loop portions adapted to project into protective position in front of the vehicle wheels and
- having inturned integral connector portions, attaching members having connector portions adapted to coöperate with the connector portions of said buffer front member and having alining action in connection with the alining flanges thereof and clamping means securing together the coöperating connector portions. 25
12. The automobile buffer comprising a resilient strip buffer front member having end portions adapted to project into protective position, in front of the vehicle 30 wheels and having inwardly extending connector portions formed with alining flanges, attaching members having connector portions adapted to adjustably coöperate with the connector portions of said buffer front member and the alining flanges thereof and clamping means adapted to engage the coöperating connector portions adjacent each end of the buffer and forcing the same together. 35 40
